(57) CLAIM

The ornamental design for a video game joystick cover, as shown and described.

DESCRIPTION

FIG. 1 is a front elevation view of a video game joystick cover showing my new design, the opposite side being a mirror image of the shown;

FIG. 2 is a left elevation view thereof;

FIG. 3 is a right elevation view thereof;

FIG. 4 is a top plan view thereof;

FIG. 5 is a bottom plan view thereof; and,

FIG. 6 is a perspective view thereof, shown in its environmental use.

The broken lines in the drawings depict environmental subject matter only and form no part of the claimed design.
